UNITED STATES PATENT OFFICE

2,452,063

DETONATOR DISK

Harry Liber, Morristown, and Donald R. Beeman,
Wharton, N. J.

Application February 19, 1947, Serial No. 729,641

1 Claim. (Cl. 102—86.5)

(Granted under the act of March 3, 1883, as
amended April 30, 1928; 370 O. G. 757)**1**

The invention described herein may be manufactured and used by or for the Government or governmental purposes without the payment of us of any royalty thereon.

This invention relates to a detonator disc of special design which increases the structural strength of detonators and improves their ability to withstand severe rough handling.

In detonators having conventional flat discs, severe rough handling such as that encountered in handling and transportation, frequently causes the unseating of the disc and the spilling of the charge and consequent failure of the detonator function.

The object of this invention is to prevent such failure by use of a cup-shaped detonator disc whose tapered construction, by creating a stronger bond with inside wall of detonator holder, strengthens the construction of the detonator which is further strengthened by the pressure of the charge upon the disc when detonator is loaded. This strengthening enables the detonator to withstand handling more severe than is possible with flat discs.

In the accompanying drawing, Figure 1 is a sectional view of rotor assembly containing detonator; Figure 2 is a similar view of a detonator assembly containing cup-shaped disc; Figure 3 is a plane view of cup-shaped disc and Figure 4 is a sectional view of cup-shaped disc showing tapered wall feature.

In Figure 2, cup shaped disc *a* is seated in detonator *b* major diameter of disc *c* being slightly larger than the inside diameter of detonator holder thereby creating a light force fit with wall of detonator holder *d* at point of juncture *e* pressure of explosive charge *f* creates further force

2

at point *e* which materially improves the strength of the detonator assembly.

We claim:

5 A detonator comprising a cylindrical member containing an explosive charge and a cup-shaped disc retaining member, said charge being retained in said cylindrical member by said cup-shaped disc positioned in one end of said cylindrical member, said disc having tapered walls the major and minor diameters of which are respectively larger and slightly smaller than the inside diameter of said cylindrical member, said walls directed inwardly of said end and towards the longitudinal axis of said charge when fitted to 10 said cylindrical member and creating a force fit with the inner wall of said cylindrical member which in combination with the pressure exerted by said charge increases the structural strength of said cylindrical member radially at 15 said end.
